FLUID PUMP CONSTRUCTION

Edward Levy Mayo, Cleveland, Ohio, assignor to
The Bishop & Babcock Manufacturing Company, Cleveland, Ohio, a corporation of Ohio

Application March 6, 1934, Serial No. 714,354

7 Claims. (CL 103—23)

The present invention relates to improvements in pumps for automotive liquid cooling circulatory systems for internal combustion engines.

In the use of internal combustion engines having liquid cooling systems, it has commonly been the practice, particularly in connection with automobiles to provide thermally operated valves to vary the flow of or entirely throttle the flow of the water or other cooling liquid to restrain or prevent circulation of the liquid until and except at such times as the liquid has achieved or maintains a given predetermined minimum temperature.

In such systems, a pump is employed as a separate piece of mechanism elsewhere in the system to induce the flow of liquid through the system and the throttling of the flow by the valve device has imposed an increased load on the pump.

Such throttling devices have been employed for the purpose of enabling an engine to "warm up" faster than otherwise would be the case, and are of particular value where a by-pass of the liquid cooling circulatory system is employed in which there is incorporated a hot water heater for the passenger compartment of the vehicle. At the same time such throttling devices are additionally useful for the purpose of reducing the amount of condensation of the volatile fuel used in the engine, such condensation leaking past the piston rings and diluting the crank case lubricant, during periods when a cold engine is being started and a necessarily "rich" mixture is supplied to the engine.

The present invention has for a primary object to provide as a unitary device a pump which is thermally operative to pump liquid through the system only when the liquid has achieved a predetermined temperature value.

Another object of my invention is to provide improved means for starting and stopping a liquid circulating pump for an internal combustion engine upon temperature changes of the cooling medium.

Another object is to provide, in a pump of the class referred to, means for automatically starting and stopping it in correspondence with temperature conditions of the engine.

Another object is to provide a pump for circulating liquid in the cooling system of an internal combustion engine having a continuously operating power take-off from the engine and comprising means automatically responsive to predetermined high and low temperatures of the liquid in the cooling system to render the pump

respectively effective and ineffective to circulate the liquid in the system.

Other objects will be apparent to those skilled in the art to which my invention appertains.

My invention is fully disclosed in the following description taken in connection with the accompanying drawing, in which:

Fig. 1 is a side elevational view of an internal combustion engine and cooling system and illustrating an embodiment of my invention applied thereto;

Fig. 2 is a sectional view to an enlarged scale of a part of the apparatus of Fig. 1.

Referring to the drawing, I have shown generally at 1 an internal combustion engine comprising a base 2 and head 3 internally formed to provide the well known water jacket. A radiator 4 communicates by a conduit 5 with the water jacket at a point in the lower portion of the base 2 and the upper portion of the radiator 4 communicates through a conduit 6 and a pump shown generally at 7 with an upper portion of the water jacket, for example that portion in the head 3. The pump 7, to be more fully described, is driven by a shaft 8 through the agency of a pulley 9 on the shaft and a belt 10 on the pulley 9 and a driving pulley 11 driven by a shaft 12 from the crank shaft of the engine in a well known manner.

The pump 7, by a construction and mode of operation to be described, circulates cooling liquid such as water through the cooling system above referred to to prevent the engine temperature from rising to undesirably high values. When the engine is cold or while it is warming up after starting, the pump, although receiving power, develops no pressure and effects no forced circulation. The cooling liquid therefore, particularly that in the engine jacket, rapidly warms up, permitting the engine to warm up to an efficient temperature. When, however, a predetermined temperature has been reached, the continuously driven pump begins to circulate the cooling liquid through the system thereby preventing or substantially preventing any further rise of temperature. The pump construction by which this is accomplished will now be described.

A pump housing 13 has a pump chamber 14, and an outlet conduit portion 15 and an inlet conduit portion 16, adapted to be connected respectively to the conduit 6 and to the head 3 of the engine. A pump rotor comprising vanes 17—17, any suitable number of which may be provided, is mounted to rotate in the chamber 14. The vanes 17—17 extend outwardly radially from

a cup-form rotor head 18, the cup bottom of which is rigidly connected to a rotor shaft 19. A recess 20 is formed preferably at the center of the cup bottom 21, and a threaded stud 22 having a collar 68 intermediate its ends, has the end 69 opposite its threaded end, projected through a perforation 70 in the recess bottom, and riveted over inwardly of the cup bottom to rigidly mount the stud 22 on the cup bottom with the threaded end thereof projecting outwardly axially therefrom. The rotor shaft 19 has its inner end threaded upon the stud 22 and seated in the recess 20 to rigidly secure it to the cup bottom. Solder may be applied at the junction of the stud 22 with the cup bottom to render it leak proof for a purpose that will be apparent.

The rotor shaft 19 is rotatably mounted in a pair of axially spaced bearings 23-23 in a bearing housing 24 formed to provide a lubricant chamber 25 intermediate the bearings 23-23 from which the bearings receive lubricant. An annular recess 26 is formed in the bearing housing 24, generally coaxial of the shaft 19 and open toward the cup bottom 21. The recess 26 has a radially outer generally cylindrical wall 27 and a generally cylindrical radially inner wall 28 and an annular bottom 29. A bearing washer 30 of fiber or like material has bearing engagement with the outer axial end of the cup bottom 21, the washer having a central perforation which surrounds with clearance the wall 28 and the peripheral edge of which is splined upon splines 31 upon the inner wall 27 to prevent rotation of the washer but to permit free axial movement thereof.

35 A sheet metal shallow cup 32 has a large central perforation in the bottom thereof by which it is telescoped over the wall 28 and has seated therein a cork ring 33 sealingly fitting the wall 28 by its inner periphery and by an annular surface thereof 40 sealingly engaging the bearing washer 30. A compression spring 34 abuts at opposite ends upon the recess bottom 29 and upon the bottom of the cup 32. The outer end of the rotor shaft 19 has a collar 35 secured thereon as for example by a 45 pin 36 projected through the collar and through the shaft and has thrust bearings as at 37 upon the bearing housing 24.

The bearing housing 24 as a whole may be supported generally coaxially with respect to the 50 conduit portion 16 of the pump housing 13 by a plurality of radially disposed spokes 38-38 connecting the wall 39 of the housing portion 16 with the bearing housing 24. A free liquid flow passageway is thus provided through the conduit 55 portion 16 into the pump chamber 14 and around the bearing housing 24.

A lubricant duct 40 may provide communication to the exterior of the housing from the lubricant chamber 25 whereby, by well known means, 60 lubricant under pressure may be supplied to the chamber 25 and may be caused to supply lubricant to the bearings 23-23 and to the end thrust bearing 37, and to the bearing between the bearing washer 30 and the cup bottom 21 and to the 65 seals effected by the cork ring 33. When the housing 13 in general is filled with water in the operation of the pump, water is prevented from leaking into the lubricant system just described by the pressure engagement at the end thrust 70 bearings 31 and 30-21, end thrust being maintained at both of these bearings by the spring 34, and water which may leak through the spline connection 31 will be trapped in the recess 26 by the seal effected by the cork ring 33.

75 Telescoped within the cup-form rotor head 18

is an inner cup 41 substantially fitting but axially slidable within the head 18. A bellows type thermostat 42 is sealed at opposite ends upon the cup bottom 21 of the head 18 and the axially opposite cup bottom 43 of the inner cup 41. Externally, the cup bottom 43 is provided with a frusto-conical clutch element 44 and axially through the clutch element 44 and cup bottom 43, expandible fluid material may be inserted into the bellows 42. To this end, the clutch element 44 10 may have a stem 45 projected through a suitable perforation in the cup bottom 43 and adapted to be riveted over as at 46 internally of the cup, and a suitable duct 47 may be provided through the stem 45 through which the expandible thermostatic fluid may be injected into the bellows and then the duct sealed in a well known manner as at 48.

A plurality of radially extending pins 49-49 are secured to the inner cup 41 and extend outwardly through axially extending slots 50-50 in the wall of the rotor head 18, thus providing a spline connection between the inner and the outer cups above described, whereby rotary power when applied to the inner cup in a manner to be described may rotate the rotor head. A plurality of radially aligned openings 51 and 52 may be provided respectively in the walls of the cups 18 and 40 41 whereby water in the pump housing may flow into contact with the outer wall of the bellows 42 30 to communicate its temperature thereto.

A driving shaft 53 is mounted, preferably coaxially of the rotor shaft 19 in axially spaced bearings 54-54 in a housing 55, and upon the outer end of the shaft 53 the pulley 56 may be rigidly secured and the hub of the pulley may have end thrust bearing as at 56 on a portion of the housing 55. The inner end of the shaft 53 is provided with a head 57 having a preferably frusto-conical clutch recess 58 therein 40 formed to mate with the clutch element 44 in a manner to be described to effect clutching engagement between the shaft 53 and the rotor head 18. The clutching surfaces may preferably be as shown roughened or serrated, or may be made smooth as desired according to the kind of materials used, the thermally effected pressures operating the clutch and the area of the clutch surfaces. A bearing washer 59 is splined as at 60 upon an inner wall of the housing 55 50 and effects end thrust bearing with the head 57. A shallow cup 61, cork ring 62, spring 63 and lubricant chamber 64 are provided corresponding to the parts 32, 33, 34, and 25 above described.

It is believed that without further description, in view of the more complete description of the corresponding parts above referred to, it will be clear that the spring 63 effects end thrust to hold the bearing washer 59 against the head 57, this end thrust being counter-acted by the end 60 thrust bearing 56 and that lubricant from the chamber 64 may lubricate the bearing surfaces thus provided and that the cork ring 62 and the seals effected thereby and by the bearing washer 59 will prevent water in the pump chamber 14 65 from leaking out therefrom through the lubricated bearing system described.

In the operation of the pump construction above described, when the water in the cooling system is relatively cool, this water in the conduit portion 16, passageways around the spokes 38 70 and in the pump chamber 14 and conduit portion 15 will communicate its temperature to the bellows 42 and permit it to remain in its contracted position illustrated. The pulley 56 re- 75

ceiving rotative power from the engine continuously rotates the shaft 53 and the clutch head 57, but without communicating this movement to the rotor head 18 due to the fact that the clutch element 44 is retracted axially from the clutch recess 58 by the bellows.

When the temperature of the water in the engine jacket rises, it will be communicated to the bellows 42, causing it to expand. By the time 10 the water temperature has reached a value at which it becomes desirable to circulate the water through the radiator to prevent further rise of temperature, the bellows 42 will have been heated thereby sufficiently to expand it and cause the 15 clutch element 44 to be moved toward the left axially as viewed in the drawing into engagement with the clutch recess 58, thereby clutching the rotor head 18 to the rotating shaft 53 and rotating the head 18 and therewith the pump 20 vanes 17-17. Pumping pressure is thereby immediately generated and the water is forceably circulated through the system above described.

To aid the expanding movement of the bellows 42 effecting engagement of the clutch means, I 25 preferably dispose therein a compressed spring 70 having its end convolutions abutting the cup bottoms 21 and 43. A spring 70 also limits contracting movement of the bellows 42.

If, due to any cause, the water temperature 30 should fall to or below the desired efficient engine temperature, the reduction of temperature will be communicated to the bellows 42 and it will contract sufficiently to disengage the clutch element 44 and the clutch recess 58 and stop 35 further rotation of the pump vanes 17-17 and stop forced circulation of the water. Thus when the water is at or below a predetermined low temperature, there will be no forced circulation through the radiator but whenever it is at or 40 above a predetermined higher temperature, forced circulation will be maintained.

In order to prevent a thermo-syphon effect 45 tending to cause circulation of liquid through the system when the pump is at rest, I have provided a check valve herein shown as being of ball type having a valve ball 67 and an annular valve seat 65 disposed within the conduit 15 on the discharge side of the pump, together with a grid 66 in said conduit in spaced relation to the 50 valve seat 65 to restrain the ball 67 from dis- placement in the circulatory system from a position wherein it will again be seated when the pump is again inoperative.

It will be readily understood that the ball 67 55 will be carried from its seat when the pump is in operation by liquid forced from the pump but that at all other times its weight will be sufficient to retain it on its seat to restrain undue thermo-syphon circulatory currents of the cooling me- dium through the system.

My invention is not limited to the exact details 60 of construction shown and described. Many changes and modifications may be made within the spirit of my invention without sacrificing its advantages and without departing from the scope of the appended claims.

I claim:

1. In a fluid pump construction, a walled conduit means, a pump rotor in the conduit means, 70 a rotary driving shaft extending through a wall of

the conduit means supporting a first clutch element, a driven shaft in the conduit means supporting the rotor, a second clutch element supported by the driven shaft and movable axially relative thereto, and a thermostat responsive to temperature changes of rotor pumped fluid to move the second clutch element into and out of engagement with the first clutch element. 5

2. In a fluid pump construction, a walled conduit means, a pump rotor therein, a shaft in the conduit means supporting the rotor, a clutch element on the rotor movable axially relative thereto, a thermostat for moving the clutch element, and a driving shaft extending through a wall of 10 the conduit means carrying a clutch element engageable by the thermostat movable clutch element. 15

3. In a fluid pump construction, a rotatably supported rotor comprising a pair of hollow axially telescopic rotor head elements, vanes on one 20 of the head elements, a clutch element on the other head element, and a thermostat within the head elements effecting relative axial movement therebetween, a rotary driving element provided with a clutch element disposed to be engaged by the head carried clutch element upon thermostatic effective movement thereof. 25

4. In a fluid pump, a housing, a pair of driving and driven shafts having portions in the housing substantially axially aligned and spaced apart, a 30 pump rotor in the housing comprising a hollow central head on the driven shaft and carrying an axially movable driven clutch element, and a thermostat for effecting axial movement of the clutch element, a mating clutch element carried 35 by the driving shaft engageable by the driven clutch element.

5. In a fluid pump, a housing, a pair of driving and driven shafts having portions in the housing substantially axially aligned and spaced apart, 40 a pump rotor in the housing comprising a hollow central head on the driven shaft and carrying an axially movable driven clutch element, and a thermostat for effecting axial movement of the clutch element, a mating clutch element carried 45 by the driving shaft engageable by the driven clutch element, the thermostat effecting axial thrust on the driving shaft and a sealed thrust bearing for the driving shaft.

6. In a fluid pump construction, a walled conduit means, a pump rotor therein, a driven shaft supporting the rotor, a driving shaft extending into the conduit means through a wall thereof substantially aligned with the driven shaft, confronting clutch elements supported by the shafts 55 respectively, a thermostat for engaging the clutch elements exerting opposite thrusts on the shafts, and a thrust bearing sealing the driving shaft with respect to the conduit means wall. 50

7. In a fluid pump construction, a walled housing, a pump rotor rotatably supported in the housing comprising an axially expandible head having pump vanes thereon, an axially movable clutch element carried by the head in the housing, a thermostat for moving the clutch element, 65 a driving shaft extending into the housing carrying a clutch element engageable by the thermostat movable clutch element. 60
